UNITED STATES PATENT OFFICE.

PERCY PIERCE, OF PHILADELPHIA, PENNSYLVANIA.

TOY AEROPLANE.

Application filed November 26, 1921. Serial No. 517,915.

To all whom it may concern:

Be it known that I, PERCY PIERCE, a citizen of the United States, and a resident of Philadelphia, county of Philadelphia, State of Pennsylvania, have invented certain new and useful Improvements in Toy Aeroplanes, of which the following is a specification.

Some of the objects of the present invention are to provide an improved aerial toy arranged to fly in simulation of an aeroplane; to provide a blank of suitable material arranged to be folded in such a way as to produce a complete aeroplane which when thrown will fly in realistic manner; to provide a one piece blank so shaped and arranged as to be readily folded into aeroplane form; to provide an improved folded toy aeroplane having means to sustain and stabilize the aeroplane in flight; to provide means for reinforcing the sustaining wings of a toy aeroplane; and to provide other improvements as will hereinafter appear.

In the accompanying drawings, Fig. 1 represents a plan of a blank for forming a toy aeroplane embodying one form of the present invention; Fig. 2 represents a plan of the aeroplane showing one step in its construction; Fig. 3 represents a plan of the completed aeroplane as formed by folding the blank of Fig. 1; Fig. 4 is a side elevation of the completed aeroplane; Fig. 5 is a front elevation of the same; Fig. 6 represents a plan of a blank for forming a toy aeroplane embodying another form of the present invention; Fig. 7 represents a perspective of a detail of construction employed with the aeroplane of Fig. 6; and Fig. 8 represents a perspective of the completed aeroplane, formed from the blank of Fig. 6, in launching position.

Referring to Figs. 1 to 5 of the drawings one form of a toy aeroplane embodying the present invention is shown comprising a blank 10 cut from any suitable material, such as a relatively stiff paper or any other readily shaped sheet.

For the purpose of forming the fuselage of the aeroplane, the blank 10 has an elongated, longitudinally disposed body 11 having a rearwardly tapered portion 12 which terminates in an outwardly flared tailpiece 13, the extremity of which is provided with two oppositely arranged lateral projections 14 having rounded ends respectively.

In order to provide supporting planes for

the aeroplane, the body 11 has two wings 15 extending in opposite directions and in aligned relation, and forming a slight dihedral angle, while their respective front edges are in the same straight line passing at right angles to the longitudinal axis of the body.

As a means for stabilizing the aeroplane in flight, the tail piece 13 is provided with oppositely disposed laterally projecting elevating wings 16 which are relatively small as compared to the sustaining wings 15. The respective outer edges 17 of the wings 16 curve outwardly and rearwardly so that the surface exposed to the air gradually increases in area toward the tail of the aeroplane.

If it is desired to provide a figure simulating an aviator, the blank 10 is provided at the front of the body 11 with an extension support 20 having flap members 21 formed thereon for the purpose of simulating a human figure by printing thereon or otherwise.

For the purpose of protecting the front edge of the respective sustaining wings 15 and also maintaining them in correct position for proper flying, a strip 22 is provided, preferably of thin metal, to give the necessary rigidity but of sufficient ductility to be readily bent to the desired shape. This strip 22, when folded lengthwise, is fitted over the front wing edges from tip to tip and pressed so that it is firmly clamped to the blank material, thereby forming a rigid reinforcement which prevents damage to the wings 15 in flight. Also this reinforcement strip 22 steadies the aeroplane and counteracts the effect of air currents tending to disturb the balance. While it is preferable to employ a metal strip 22, it will be understood that any other suitable material giving the desired result may be employed. The blank 10 with its attached strip 22 is shown in Fig. 2, with the aviator support 20 folded back to position, ready for the complete folding operations.

To form the aeroplane the blank 10 is first folded along the medial line, indicated dotted at 23 in Fig. 2, after which one wing 15 is folded outward along dotted line 24, and the other wing 15 is folded outward along dotted line 25. Those operations provide the substantially vertical fuselage body 11 having vertical rudders 26 and the substantially horizontal side wings 15, the area

of which is such as to sustain the body in the air when propelled with sufficient force. The stabilizing wings 16 are now formed by folding the tail portion 13 along the respective dotted lines 27 and 28 to give a forward pitch to the upper surface of the wings 16. As seen in Figs. 4 and 5, the construction is such that the inclined wings 16 are to the rear of the wings 15 and below them, and consequently they are exposed to the current of air passing rearwardly under the wings 15 and function to hold the tail piece 13 down so that the aeroplane is maintained in flying position instead of making a nose dive as soon as thrown. It will be noted also that the stabilizing effect is insured by proportioning the area of the wings 16 with respect to the weight of the strip 22 to give the desired equilibrium.

In Figs. 6 and 7 another form of blank 30 is shown for use with a reinforcing strip 31 of cardboard or like stiffening material. In this form the blank 30 is provided with flaps 32 formed on the front edge and arranged to be folded on dotted lines 33 into superposed relation with the strip 31 which is laid flush with the front edge and pasted in place. Where an aviator member 34 is employed, it is preferable in this form to employ a separate piece 35 which is pasted to the body or fuselage 36. After the body is folded it is held closed and rigid at the front by a small flap 37 which is arranged to be folded around the fuselage end and pasted against the opposite side. This not only holds the folded portions firmly but gives a reinforcement to the part held in throwing the device. To further strengthen the position of the body where it is held for throwing, and also to reinforce the bent portion of the strip 31, there is an auxiliary strip 38 pasted across from one wing 40 to the other wing 41 before the flaps 32 are pasted down in place.

From the foregoing it will be apparent that in either form of the invention a complete flying toy is provided wherein stability with sustaining power causes the aeroplane to fly smoothly in a given direction, without the usual darting or diving motions common to toys of this character. Any tendency of the aeroplane to fall into a nose dive is compensated for by the arrangement of the small elevating wings 16 on the tail because the applied force of the air acts against their top surface in opposition to the gravity pull of the reinforcement strip 22. These wings 16, like the sustaining wings 15, project laterally from the body 12 and form a slight dihedral angle with each other in the same manner as do the wings 15, so that the entire structure functions to prevent improper tilting about either a horizontal or a vertical axis.

Attention is also directed to the simplicity of construction in that a one piece blank serves to form the aeroplane body, the wings, the stabilizing means and the tail, the whole being stamped or cut out at one operation ready for the folding operations. It will be noted that the strip 22 preferably extends the full length of the front edge of the wings 15, thereby giving the required rigidity of construction and balance to the parts.

Having thus described my invention, I claim:

In a toy, a one piece blank folded to form an aeroplane having a fuselage, sustaining wings, elevating wings and a tail rudder, in combination with a strip of reinforcing material superimposed upon the front edge of said sustaining wings and extending the full length thereof.

Signed at Philadelphia, county of Philadelphia, State of Pennsylvania, this 17th day of November 1921.

PERCY PIERCE.
